CLAIM

The ornamental design for an arm-receiving door pull, as shown and described.

DESCRIPTION

FIG. 1 is a front, top, and right side perspective view of an arm-receiving door pull, showing our new design in use; FIG. 2 is a front, top, and left side perspective view thereof; FIG. 3 is a front elevational view thereof;

FIG. 4 is a rear elevational view thereof not shown in use for clarity of illustration;

FIG. 5 is a left side elevational view thereof; and,

FIG. 6 is a right side elevational view thereof.

Broken lines are for illustrative purposes only, and form no part of the claimed design.
